[57] CLAIM

The ornamental design for a boat fender cover, as shown and described.

DESCRIPTION

FIG. 1 is a rear elevational view of a boat fender cover showing my new design, the front view is plain;

FIG. 2 is a front elevational view of a second embodiment of the boat fender cover, the rear view is identical to FIG. 1;

FIG. 3 is a rear perspective view of either FIG. 1 or FIG. 2, showing the cover unwrapped condition;

FIG. 4 is a plan view of FIG. 2 in an open condition;

FIG. 5 is a front perspective view of a third embodiment of the boat fender cover;

FIG. 6 is a front perspective view of a fourth embodiment of the boat fender cover;

FIG. 7 is a front perspective view of a fifth embodiment of the boat fender cover;

FIG. 8 is a front perspective view of a sixth embodiment of the boat fender cover;

FIG. 9 is a rear perspective view of a seventh embodiment of the boat fender cover, the front view is plain;

FIG. 10 is a front perspective view of an eighth embodiment of the boat fender cover, the rear view is identical to FIG. 9;

FIG. 11 is a front perspective view of a ninth embodiment of the boat fender cover, the rear view is plain; and,

FIG. 12 is a bottom plan view of FIG. 11.

The rear view of FIGS. 5, 6, 7 and 8 being identical to FIG. 1. The broken lines shown in FIGS. 1, 2 and 11 are for illustrative purposes only and forming no part of the claimed design.
